United States Patent

Des. 237,895

Patented Dec. 2, 1975

237,895

FIRE EXTINGUISHER

Louis F. Allen and Joseph B. Ott, Erie, Pa., assignors to
Conwed Corporation, St. Paul, Minn.

Filed Aug. 22, 1973, Ser. No. 390,367

Term of patent 14 years

Int. Cl. D29—01

U.S. Cl. D32—2

FIG. 1 is a fragmentary perspective view of the fire extinguisher showing our new design;

FIG. 2 is a fragmentary side elevational view, with the hose and its connection omitted for ease of illustration;

FIG. 3 is a top plan view;

FIG. 4 is a side elevational view showing the side opposite that shown in FIG. 2; and

FIG. 5 is a rear elevational view.

The bottom is plain.

We claim:

The ornamental design for a fire extinguisher, as shown and described.
